UNITED STATES PATENT OFFICE.

ARNOLD STUCKI, OF PITTSBURGH, PENNSYLVANIA.

ROLLER SIDE BEARING.

1,187,675.

Specification of Letters Patent. Patented June 20, 1916.

Application filed September 23, 1913. Serial No. 791,337.

To all whom it may concern:

Be it known that I, ARNOLD STUCKI, a resident of Pittsburgh, in the county of Allegheny and State of Pennsylvania, have invented a new and useful Improvement in Roller Side Bearings, of which the following is a specification.

This invention relates to side bearings for railway cars.

- 10 The object of the invention is to provide a side bearing which is practically frictionless, which works properly under all service conditions, whether normal or abnormal, and which performs all other functions of 15 side bearings; which has a large bearing surface and is durable in service; one in which the working parts are easily inspected but at the same time are securely locked in place, which embodies novel and 20 improved means for preventing the anti-friction member from becoming displaced on the bearing surface, and which is simple in construction, and therefore inexpensive both as to first cost and as to up-keep.
- 25 The invention comprises the construction and arrangement of parts hereinafter described and claimed.

In the drawings, Figure 1 is a plan view of a side bearing embodying the invention; 30 Fig. 2 is a vertical longitudinal section thereof on the line 2--2 Fig. 1; and Fig. 3 is in part an end view and in part a vertical cross section thereof.

As illustrated in the drawings, the bearing 35 comprises a suitable frame or housing 1 arranged for attachment to the bolster 2, but which may be integral with said bolster if desired. The frame or housing is adapted for a straight bolster, but may be readily 40 adapted to a tapering bolster. It is provided with a bottom 3, side walls or barriers 4, end walls or barriers 5, and with suitable ears or lugs 6, perforated for the reception 45 of rivets or bolts for securing the said frame or housing to the bolster.

The bottom 3 provides a wide and extensive bearing surface for the anti-friction member 7, which bearing surface may be either integral with the bottom, or, as shown, 50 may be formed by a separate plate or member 8 riveted or otherwise secured to the frame or housing. This permits the bottom to be formed of spring steel, which is sufficiently hard, and is very efficient as a bearing 55 surface. The anti-friction member is shown as a plain-faced roller 7, which has

a rolling movement to and fro along the bearing surface. As it makes only a partial rotation in each direction, it is in effect a rocker member and need not necessarily be 60 circular in cross section so long as it has sufficient curved surface to rock on the bottom bearing surface and to contact with and roll along the upper bearing member or bolster 2. The roller may also be made 65 slightly conical or tapering instead of cylindrical, in which event the housing will be curved on an arc to correspond to the taper of the cone. The bearing surface 8 on which the member 7 rocks or rolls is shown as level 70 or horizontal from end to end, so that the member 7 travels thereon without other than rolling friction, and without the necessity of lifting the car body as it rocks or rolls toward the ends of the housing or frame. The 75 bearing therefore permits a freer swiveling of the truck underneath the car body in approaching, passing and leaving a curve, as the roller does not have to roll up an incline.

80 The side and end walls of the frame or housing are for the purpose of confining the rocking member and preventing it from escaping under normal operating conditions, and are therefore of material height, extending fairly close to the top of the member 7. The end walls or barriers 5 have their upper portions substantially vertical, as shown in Fig. 2, so that the roller 7 cannot roll up over the same, said end walls forming absolute steps to limit the travel of the rocking member in both directions. The top edges of the side and end walls are broad and flat and form an efficient and satisfactory side bearing even if the roller is lost in 90 a wreck or from other causes.

To prevent the housing from accumulating dirt, which would clog the movement of the rocking member, the walls are preferably of open or skeleton construction, the 100 end walls being provided with large openings 11 extending for the full width of the housing, part way along its bottom, and for a considerable distance upwardly, while the side walls 4 are provided with large openings 12 near the end portions thereof. As a consequence the walls or barriers are practically supported upon posts or columns 13, leaving large openings at the level of the bearing surface both at the ends and sides, 105 through which snow, ice, dust, dirt and other foreign material can readily escape, so as to

prevent retarding the movement of the rocking member. The side and end walls or barriers are strengthened and stiffened by horizontal ribs or flanges 14 and vertical 5 ribs or flanges 15.

- It is desirable to provide suitable means for returning the rocking member to central position in the frame or housing whenever the bolsters separate, in order that it may be 10 in proper position when the bolsters again come together and move relatively to each other. On account of the level or horizontal position of the bearing surface 9, an ordinary roller would not automatically return 15 to central position upon separation of the bolsters. To provide for this the rocker member or roller is arranged to return to central position by a counterpoise acting by gravity. As shown, the roller 7 is provided 20 with an opening or openings 16 on one side of its geometric axis, leaving the opposing side 17 solid so that its center of gravity is not at the geometric axis but somewhere within the solid and heavier portion 17. 25 Consequently, on a horizontal surface this roller will come to rest with its center of gravity as low as possible, or in the position shown in Fig. 2. The result is that it is self-centering by gravity whenever the bolsters separate. Preferably, and as shown, 30 the roller 7 is made of a hollow cylindrical steel shell, one side of which is weighted by casting a mass 18 of lead or other heavy metal therein and allowing it to cool.
- It is also desirable to provide means to prevent the rocking member from shifting on the bearing surface so that it cannot become displaced under heavy end shocks or sudden longitudinal blows on the car. This 35 result may be secured in several ways. As shown, the roller 7 is provided at each of its ends with a pin or trunnion 19, said trunnions preferably being arranged opposite each other, or with their axes in alinement, 40 and projecting from the solid or heavier portion 17 of the roller below the center of gravity thereof. The side walls of the frame or housing 1 are shaped to provide curved guides or runways 20, the lower edges 21 of 45 which are curved to conform to the path taken by the trunnion 19 as the roller moves back and forth along the bottom bearing surface. Said guides or runways are formed by outwardly projecting portions 22 of the 50 housing or frame, which considerably reinforce and strengthen the same.
- In use of the bearing the roller 7 traverses back and forth along the bottom bearing and the two trunnions 19 travel substantially in 55 contact with the edges 21 of the guideways 20, which therefore prevent displacement of

the roller along the bearing surface under heavy end shocks or blows. When the trunnions are axially in line with each other, as shown, the roller is prevented from becoming 65 tilted or askew, as both trunnions contact the guides at the same time, whenever the roller tends to shift on the bearing surface. One end portion of each of the guideways 20 extends upwardly and is provided with an 70 opening 23 at the upper edge of the housing. This permits the rollers to be readily dropped into place, but the close spacing between the upper and lower bearing members in use of the bearing practically closes said 75 opening and locks the roller in place, preventing it from becoming lost.

The pins or trunnions 19 are on the heavier side of the roller 7, and consequently amplify the eccentric loading thereof, so that the 80 roller more readily returns to central position when moved therefrom.

In the bearing described the roller or rocking member is free to roll or travel on a 85 level or horizontal surface without other than rolling friction and without either rising or falling upon swiveling of the truck and by reducing friction assists in the free swiveling thereof. The pins or trunnions and the co-operating guides or runways prevent the roller from shifting out of normal 90 position by end shocks of the car. At the same time this arrangement does away with the necessity of special parts on the contacting surfaces of the roller and bottom bearing members. The construction is simple, 95 all of the parts being adapted for easy inspection and the entire bearing is self cleaning so that it is very efficient in operation.

What I claim is:

A side bearing for railway cars, comprising a housing for the lower bolster having its bottom forming a bearing surface and provided with side and end walls or barriers having flat upper bearing surfaces and openings at the level of the bottom bearing surface, and an eccentrically loaded roller resting on said bottom bearing surface and having its heavier portion provided with end trunnions, said side walls being provided with curved guideways for co-operation with said trunnions, the active portions of said guideways being extended upwardly and opening through the upper edges of the 105 housing walls to permit insertion of the 110 roller into the housing.

In testimony whereof, I have hereunto set my hand.

ARNOLD STUCKI.
